DESIGN FOR A READING GLASS MOUNTING

Raoul P. Silbernagel, New York, N. Y., assignor to
Selsi Company, Inc., New York, N. Y., a corporation of New York

Application September 18, 1946, Serial No. 133,394

Term of patent 14 years

(Cl. D57—1)

To all whom it may concern:

Be it known that I, Raoul P. Silbernagel, a citizen of the United States, residing in the city of New York, Borough and county of Bronx, and State of New York, have invented a new, original, and ornamental Design for a Reading Glass Mounting, of which the following is a specification, reference being had to the accompanying drawing, forming part thereof.

Figure 1 is a front view of a reading glass mounting showing my new design.

Fig. 2 is a side view of the same.

Fig. 3 is a section through the rim of said mounting, on the line 3—3 of Fig. 1.

Fig. 4 is an end view of the same looking upwardly at Fig. 1.

I claim:

The ornamental design for a reading glass mounting, substantially as shown.

RAOUL P. SILBERNAGEL.
